ELEVATOR DOOR MECHANISM

Clifford Norton, South Orange, N. J., assignor to
 Otis Elevator Company, New York, N. Y., a
 corporation of New Jersey

Application August 1, 1935, Serial No. 34,183

15 Claims. (Cl. 187—57)

This invention relates to the operation of elevator hatchway doors and especially to the opening of locked hatchway doors from the corridor side under certain conditions.

5 In certain types of elevator installations, hatchway doors are locked in closed position against opening from the corridor side. However, it is desirable to be able to effect the opening of the hatchway door at a floor at which the car is parked from the corridor side under certain conditions, as, for example, to permit the car attendant to enter the car. It is also desirable to be able to open the hatchway door at a floor from the corridor side under emergency conditions, regardless of whether or not the car is at 10 that floor.

A feature of the invention is the provision of mechanism associated with toggle arms locking a hatchway door in closed position for preventing the opening of the hatchway door beyond a certain amount from the corridor side when the car is not at the floor at which the hatchway door is provided.

20 A second feature is the provision of mechanism whereby a hatchway door may be unlocked and opened from the corridor side, regardless of the position of the elevator car in the hatchway.

25 A third feature is the provision of mechanism rendered operable from the corridor side of a hatchway door for unlocking the hatchway door and maintaining it unlocked until the mechanism is manually reset.

30 A fourth feature is the provision of a service key operable from the corridor side of a hatchway door to unlock the door when the car is positioned at the floor at which the door is located and the provision of an emergency key to unlock the door from the corridor side regardless of whether the car is positioned at that floor or 35 not, each key being ineffective to perform the function of the other.

40 Other features and advantages will become apparent from the following description and appended claims.

45 In the drawing:

Figure 1 is an elevation of the hatchway side of a door in closed position, embodying the operating and safety mechanism of the present invention;

50 Figure 2 is a section taken along the line 2—2 of Figure 1;

Figure 3 is a front view showing an emergency key plate; and

55 Figure 4 is a view taken along the line 4—4 of Figure 2.

Referring to the drawing, a hatchway door 11 is suspended from hangers 12, which engage a track 14 to guide the door transversely of the door opening 15. Toggle arm 16 is pivotally mounted at 18 to a bracket 20 mounted on a 5 back plate 21 secured to hatchway wall 22 at one side of the stairway. Toggle arm 16 is pivotally connected at its other end to toggle arm 17, which is pivotally mounted at 23 on the hatchway door. A spring closer and check device 24, 10 pivotally connected to arm 16 and to a support 25, is provided to close and stop the hatchway door with the toggle arms in a straight line as shown in Figure 1. In this position the toggle arms constitute a positive lock against opening 15 of the hatchway door from the corridor side. Arm 17 has secured thereto a suitable grip 26, for "breaking" the toggle arms, to open the hatchway door from the elevator car.

To permit the opening of the door from the corridor side an extension 27 is positioned on toggle arm 17 opposite and all but covering the lower portion of a vertical slot 28, formed in hatchway door 11 near the rear edge thereof. Vertical slot 28 terminates in an aperture 30 on 20 the corridor side of the door. A service key 31, provided for use by an authorized elevator attendant, is inserted in slot 28 from the corridor side, for the purpose of "breaking" the toggle arms. Service key 31 is preferably of solid circular section, and of a length sufficient to gain enough leverage for conveniently breaking the toggle arms. To open the door, key 31 is inserted in aperture 30, through slot 28, down under extension 27, where an applied vertical leverage 25 35 lifts toggle arm 17 about its pivot 23, and thus toggle arm 16 about its pivot 18, to break the straight arm toggle lock whereby the door may be opened.

Mechanism is provided to prevent the opening 40 of the door from the corridor side, upon the breaking of the toggle by key 31, when the car is not at the floor at which the door is located. Such mechanism consists of a latch 33 of a bell crank 34 pivotally mounted at 35 on bracket 20. 45 Latch 33 is biased into position about pivot 35, by means to be described later, with a surface 36 held in abutment with a lug 31 positioned on toggle arm 16. Lug 31 is adapted to enter a notch 32 of latch 33 upon door opening movement. 50 As toggle arm 16 and lug 31 thereon are urged upward about pivot 18 in door opening movement, latch arm 33 follows in abutment until lug 31 enters notch 32. This locks toggle arm 16 and thus the hatchway door against further 55

opening movement. As the movement of toggle arm 16 necessary to the locking engagement of latch 33 with lug 31 is small, the door is permitted to open but a small distance.

- 5 To enable the opening of the door from the corridor side, with the car positioned at the floor, latch 33 is prevented from cooperating with lug 31 to lock the toggle arms. This may be accomplished in various ways. In the arrangement 10 illustrated, a vertical rod 37 is pivotally secured at its upper end to an arm 38 of bell crank 34, and at its lower end to an arm 40 of a bell crank 41, which is pivotally mounted on a bracket 42 fixedly supported on the landing 43. The weight of 15 rod 37 tends to urge bell cranks 34 and 41 in relative movement counterclockwise about their respective pivots. Mounted on an arm 44 of bell crank 41 is a roller 45 adapted to engage a fixed cam 46 on elevator car 47, such cam thus serving 20 as an abutment. A suitable running clearance is provided between cam 46 and roller 45 so that, as the car moves up and down in the hatchway, cam 46 passes roller 45 without contact. When, 25 with the car at the floor, key 31 is inserted in aperture 39 incident to the opening of the door, latch 33 is urged about its pivot 35 by rod 37. As latch 33 moves about its pivot, roller 45 moves across the small running clearance to contact cam 46 and, through the interconnection of rod 30 37, holds lug 31 out of notch 32, to permit the opening of the door.

It is desired under certain emergency conditions, such as a fire, to provide mechanism whereby the hatchway doors may be unlocked and opened regardless of the position of the car. Such 35 emergency mechanism generally designated 43 consists of a spring 50 held under compression between a bushing 51 positioned on support 25, and a collar 52 secured to a push rod 53 which is 40 adapted, upon upward movement, to engage the under edge of toggle arm 16. Push rod 53 is slidably guided in bushings 51 and 49 positioned on support 25 and an additional bushing 67 secured to plate 21. Collar 52 is held down against 45 the force of spring 50 by a trigger 55 secured between arms 56 and 57 which are pivotally mounted at 58 to support 25. A keeper 65 secured to arm 56 is disposed within the path of downward movement of a lug 66, adjustably secured to arm 37, upon clockwise motion of the arm.

To operate this mechanism an emergency key 64 of suitable length and preferably of a lunar or crescent shaped section, is provided. When key 55 64 is inserted in an aperture 63 formed in a key plate 62 secured to the rear door jamb, it contacts the end of an L-shaped rod 60, positioned within tube 59 formed on key plate 62. A pocket 68 formed in the hatchway wall maintains rod 60 outside the path of door opening movement (see 60 Figure 2). Pressure applied to rod 60 causes clockwise movement of arms 56 and 57, rod 60 being pivotally secured thereto at 61. Upon the clockwise movement of the arms, keeper 65 is projected within the path of downward movement 65 of lug 66, preventing rod 37 from dropping. This renders latch 33 ineffective to lock the door. Upon further movement of arms 56 and 57, trigger 55 disengages collar 52, which releases spring 50 to force collar 52 and thus push rod 53 upward. 70 Push rod 53 is forced upward against toggle arm 16 with sufficient force to lift the toggle arm, thereby breaking the toggle lock to permit the opening of the door. The toggle lock is held broken until the mechanism is reset by hand by 75 forcing push rod 53 down against the pressure of

spring 50, and by moving arms 56 and 57 so that trigger 55 again engages collar 52. This movement of the arms retracts keeper 65 from under lug 66, rendering latch 33 again effective to lock the doors.

Either the service key operated mechanism or the emergency key operated mechanism or both these mechanisms may be provided for the various doors of an elevator hatchway installation. It is preferred, however, that a combination of 10 both of these mechanisms be provided for at least one door, preferably the door at the ground floor, where the car is normally parked, and which usually would be the most advantageous entrance to the hatchway during an emergency. As previously 15 stated, authorized attendants are furnished with service keys such as key 31 to enable them to gain access to the elevator car, while it is parked at the floors provided with service key mechanisms. An emergency or fireman's key such as key 64 is 20 positioned near the hatchway entrance of each door provided with emergency mechanism. This key is preferably housed in a locked container with a "break glass" cover, to insure its use only in case of a real emergency. As previously de- 25 scribed, service key 31 is preferably of round circular section for insertion in a circular aperture 39 in hatchway door 11. Emergency or fireman's key 64 is preferably of lunar or crescent shaped section for insertion in a lunar shaped aperture 30 63 in plate 62 secured to the rear door jamb. Thus the service key cannot operate the emergency mechanism. By making the emergency key of a diameter greater than that of the service key, the operation of the service key mechanism 35 by the emergency key is also prevented. Thus, neither key can perform the function of the other.

When a door is provided with only the emergency key operated mechanism, the latch 33 and its associated mechanism may be omitted. When 40 the emergency mechanism has been operated, the hatchway door may be freely moved back and forth until the mechanism has been manually reset.

As many changes could be made in the above 45 construction and many apparently widely different embodiments of this invention could be made without departing from the scope thereof, it is intended that all matter contained in the above description or shown in the accompanying 50 drawing shall be interpreted as illustrative and not in a limiting sense.

What is claimed is:

1. In an elevator installation; a hatchway door at a floor, said door having an aperture extending therethrough; a pair of toggle arms for operating said door and for locking it in closed position; a key for operating said arms through said aperture from the corridor side of said door to break the toggle and thus unlock said door; a latch pivotally mounted in said hatchway and means on one of said toggle arms for cooperating with said latch to lock said toggle arms; an abutment carried by the car; and means associated with said latch for engaging said abutment when the car is at said floor to prevent said cooperation of said latch with said means on one of said toggle arms upon operation of the toggle arms by said key to unlock the door, said latch and said means on one of said toggle arms cooperating to prevent the engagement of said means associated with the latch with said abutment when said door is closed.
2. In an elevator installation; a hatchway door at a floor, said door having an aperture extending 75

therethrough; a pair of toggle arms for operating said door and for locking it in closed position; a key for operating said arms through said aperture from the corridor side of said door to break the toggle and thus unlock said door; a latch pivotally mounted in said hatchway and a member on one of said toggle arms for cooperating with said latch to lock said toggle arms against more than a certain amount of door opening movement; a fixed cam carried by the car; and means associated with said latch adapted to engage said cam when the car is at said floor, said latch and said member cooperating to prevent the engagement of said means with said cam when said door is closed, but acting, upon the breaking of said toggle, to permit said means to engage the cam, the engagement of said means with said cam preventing the locking of said toggle arms by said latch and member, thereby permitting the opening of said door.

3. In an elevator installation; a hatchway door at a floor; a pair of toggle arms for operating said door, said toggle arms being extended in a straight line when the door is closed to lock the door, said door having an aperture extending therethrough so as to be beneath one of said toggle arms when the door is closed; a removable key operable in said aperture for breaking the toggle from the corridor side; an arm pivotally mounted in said hatchway, said arm being provided with a notch; a lug on one of said toggle arms for entering said notch to lock the toggle arms against more than a certain amount of door opening movement; a cam carried by the elevator car; a second pivoted arm connected to said first named arm; and a roller on said second pivoted arm adapted to engage said cam when the car is at said floor to prevent movement of said first named arm about its pivot into position to permit said lug to enter said notch upon the breaking of said toggle arms, thereby permitting the opening of said door upon the breaking of said toggle by said key, said lug engaging said first named arm when said toggle arms are in extended position to hold the second named arm in position where said roller clears said cam.

4. In an elevator installation; a hatchway having an opening therein at a floor; a sliding door for closing said opening, said door having an aperture extending from the corridor to the hatchway; a pair of toggle arms, one arm pivotally mounted on the hatchway wall and the other connected to said door for operating the door, said toggle arms being extended in a straight line when the door is closed for locking the door; a removable key operable in said aperture for breaking the toggle from the corridor side; a bell crank lever pivotally mounted on said hatchway wall, one arm of said bell crank lever being provided with a notch; a lug on said one toggle arm for cooperating with said notch to lock the toggle arms against more than a certain amount of door opening movement; a rod pivotally connected to a second arm of said bell crank lever; a second bell crank lever pivotally mounted on the hatchway door sill, one arm of the second bell crank lever being pivotally connected to the lower end of said rod for joint rotative movement of the bell crank levers about their pivots, said rod and said arms of said bell crank levers connected to the rod acting to bias the first named bell crank lever into position to cooperate with said lug; a fixed cam mounted on the elevator car; and a roller positioned on a second arm of said second

bell crank lever for contacting said cam, said lug normally engaging said one arm of the first named bell crank lever to hold through said rod the second named bell crank lever in position with said roller out of the path of vertical movement of said cam, the movement of said lug, upon operation of said toggle arms by said key to unlock the door when the car is positioned at said floor, permitting said levers to swing about their pivots until said roller strikes said cam, which thereby holds said levers against further movement and prevents said lug catching in said notch, movement of the first named lever about its pivot upon the breaking of said toggle by said key when the car is not at said floor and the cam is not in position to stop such movement, causing said lug to catch in the notch, thereby locking the door against more than a certain amount of opening movement.

5. In an elevator installation; a hatchway closure at a floor; means for locking said closure in closed position; means adapted upon operation to operate said locking means to unlock said closure, said means being biased to operated condition; means for restraining said unlocking means against operation; and means operable from the corridor side of said closure for releasing said restraining means to free said unlocking means to unlock said closure.

6. In an elevator installation; a hatchway closure at a floor; a toggle for locking said closure in closed position; means adapted upon operation to break said toggle, unlocking said closure, said means being biased to operated condition; means for restraining said toggle breaking means against operation; and means operable from the corridor side of said closure for releasing said restraining means to free said toggle breaking means for operation to break said toggle.

7. In an elevator installation; a hatchway door at a floor; toggle arms for operating said door and for locking it when closed; means operable to break the toggle; means biasing said toggle breaking means to operated condition; means for restraining said biasing means; and means operable from the corridor side of said door for rendering said restraining means ineffective.

8. In an elevator installation; a hatchway door at a floor; toggle arms for operating said door and for locking it when closed; resilient means; means for maintaining said resilient means in a condition having energy stored therein; means operable from the corridor for releasing said maintaining means; and means operable by said resilient means upon release of said maintaining means to break the toggle to unlock the door.

9. In an elevator installation; a hatchway having an opening therein at a floor; a door for closing said opening; a pair of toggle arms for operating said door and for locking it in closed position; a member in the hatchway operable to break the toggle; a spring for effecting operation of said member to break the toggle; means for holding said spring in a state of compression; a key operable from the corridor to move said holding means into position to release said spring to operate said member to break the toggle, thereby permitting the opening of said door, said spring, until restored to compressed condition, acting through said member to maintain the toggle broken.

10. In an elevator installation; a hatchway, said hatchway having an opening therein at a floor; a door for closing said opening; a pair of toggle

- arms for operating said door, said toggle arms assuming a straight line position to lock the door when the door is closed; a rod positioned in the hatchway to engage one of said toggle arms and 5 movable to break the toggle; a spring connected to said rod for effecting movement thereof to break the toggle; trigger means for holding said spring in a state of compression; an extension rod connected at one end to said trigger means; a member 10 having an aperture to slidably receive the other end of said extension rod, said aperture extending into the corridor at one side of said opening; a removable key for inserting in said aperture to operate said rod, said rod upon being 15 operated by said key effecting, through movement of said trigger means, the release of said spring which acts to move the first named rod into engagement with said one toggle arm, thereby breaking the toggle to permit the opening of the 20 door, said spring holding said first named rod in position to maintain the toggle broken until said spring is again compressed.
11. In an elevator installation; an elevator car; a hatchway for said car, said hatchway having 25 an opening therein at a floor served by said car; a sliding door for closing said opening; a casing for said door in said opening; a pair of toggle arms, one arm pivotally mounted on the hatchway wall and the other arm connected to said door for 30 operating said door, said toggle arms assuming a straight line position when the door is closed to lock the door; a rod positioned in the hatchway to engage the under edge of one of said toggle arms and movable vertically to break the toggle to 35 unlock the door; a member secured to the hatchway wall for guiding said rod; a collar secured to said rod; a helical spring arranged on said rod between said member and said collar; a pivoted lever having a lug secured thereto for cooperating 40 with said collar to hold said rod in a position beneath said under edge of said one toggle arm with said spring compressed; an extension rod connected at one end of said lever; a member extending into the hatchway through one side of 45 said door casing, said member having an aperture to slidably support the other end of said extension rod, said aperture extending through said door casing to the corridor side of the hatchway door; a key plate arranged over said aperture with 50 a key hole therein of a certain contour; and a removable key for inserting in said aperture through said key hole to operate said rod, said rod upon being operated by said key effecting, through rotative movement of said lever, the release of said collar by said lug, thereby releasing 55 said spring which acts to force the first named rod upwardly against said one toggle arm, thereby breaking the toggle to permit the opening of the door, said spring holding said first named rod in 60 position to maintain the toggle broken until said spring is again compressed and said lug moved into position for cooperation with said collar to hold said spring compressed.
12. In an elevator installation; a hatchway closure at a floor; means for locking said closure in closed position; means for unlocking said closure; means for preventing the opening of said closure upon its being unlocked; means controlled by car position for rendering said preventing 65 means ineffective when the car is at said floor; additional means for unlocking said door; and means operable by said additional means for rendering said preventing means ineffective so as to enable the opening of the door regardless 70 of the position of the car in the hatchway.
13. In an elevator installation; a hatchway door at a floor; toggle arms for operating said door and for locking it in closed position; latching means for locking the toggle arms against more than a certain amount of door opening 5 movement when the car is not at said floor; means operable only when the car is at said floor for rendering said latching means ineffective to lock said toggle arms; resilient means; means for maintaining said resilient means in a condition 10 having energy stored therein; means operable from the corridor for releasing said maintaining means; means operable upon release of said maintaining means to prevent the locking of said toggle arms by said latching means; and means 15 operable by said resilient means upon release by said maintaining means to break the toggle, permitting opening of the door regardless of the position of the car in the hatchway.
14. In an elevator installation; a hatchway 20 door at a floor; toggle arms for operating said door and for locking it in closed position; a key for operating said arms from the corridor to break the toggle and thereby unlock the door; latching means for locking the toggle arms against 25 more than a certain amount of door opening movement; means operable only when the car is at said floor for rendering said latching means ineffective to lock said toggle arms; resilient means; a member arranged in the hatchway to 30 be operated by said resilient means to break the toggle; holding means for rendering said resilient means ineffective to operate said member; a second key operable from the corridor to release 35 said holding means; and means operable by said holding means upon release thereof to render said latching means ineffective to lock the toggle arms, said resilient means acting upon release of said holding means to actuate said member to break the toggle, permitting opening of the door 40 regardless of the position of the car in the hatchway.
15. In an elevator installation; a hatchway having an opening at a floor; a door for closing 45 said opening, said door having an aperture extending therethrough; a pair of toggle arms for operating the door and for locking it in closed position; a key operable in said aperture from the corridor for breaking the toggle to unlock the door; a latch pivotally mounted on the hatchway wall; a member on one of said toggle arms for cooperating with said latch to lock the toggle arms against more than a certain amount of door opening movement; means operable only when the car is at said floor for preventing cooperation 55 of said latch with said member to lock said toggle arms upon operation of said toggle arms by said key to unlock the door; a spring; a second member arranged in the hatchway to be operated by said spring to break the toggle; means for holding 60 said spring in a state of compression to prevent the toggle being broken by said second member; a second key operable from the corridor to release said holding means; means operable by said holding means upon release thereof to render said latch ineffective to lock the toggle arms, said spring acting upon release of said holding means to actuate said second member to break the toggle, permitting opening of the door regardless of the position of the car in the hatchway, said spring until again compressed acting 70 through said member to maintain the toggle broken; and means for preventing operation of said holding means by said first mentioned key.
